MONOLITHIC TRACK CONSTRUCTION

Frank H. Lehecka, East Orange, N. J., and Douglas P. Steward, Westmont Borough, Pa.

Application January 4, 1935, Serial No. 436

4 Claims. (Cl. 238—9)

This invention relates to monolithic track construction and aims to provide rail supporting means incorporated in a road bed formed in situ, of concrete, asphalt, or similar material adapted to be poured and to form a homogeneous structure. The specific features of improvement will be apparent from the following specification, the accompanying drawing and the appended claims.

In the drawing—

10 Fig. 1 is a sectional perspective illustrating the track structure embodying the invention; Fig. 2 is an enlarged cross sectional view showing one rail of the track, one chair and related parts; Fig. 3 is a reduced scale perspective view showing the chair.

15 Referring in detail to the drawing, 10 may be regarded as a body of either concrete cast in situ, or a substantially homogeneous body of asphalt or the like. Embedded in this body are the track rails 12—12, which in the embodiment illustrated are of the type frequently used in street railway work having a head portion 14 and a flangeway 16. However, T-rails or other conventional types may be employed. The rail base 18 is accommodated in the centrally depressed portion 20 of the rail chair, indicated as a whole at C.

20 The chair is formed of bar stock such as rolled steel. This stock is bent or forged to a shape substantially corresponding to that shown in Fig. 30 2. This configuration of the chair provides shoulders 22—22 which are effective to resist lateral movement of the rail. In a plane above the depressed portion, there are clip bearing surfaces 24—24. Downwardly and outwardly extending therefrom, there are supporting legs 26 which terminate in curved feet 28. These feet are adapted to rest on blocks or any suitable form of support or falsework 30 during the time of pouring or casting the monolithic road bed.

35 40 Hold down clips 32 have downwardly bent portions 34 which fulcrum on the surfaces 24 and the ends 36 thereof are forcibly clamped to the rail base by means of nuts 38 threaded on the hold down bolts 40. The heads 40 of the holding bolts 45 are prevented from turning because of the close proximity to the shoulder portions 22 of the chair.

45 The track gauge is maintained by spacing members 42 which are riveted or otherwise secured, as indicated at 44 to the legs 26 of the chair.

50 Interposed between the depressed bearing portion of the chair and the underside of the rail base, we provide a body 46 of material which is relatively yieldable as compared with the rigidity 55 of the concrete or cementitious monolithic road

bed. This cushioning material may be of asphalt or other readily cast or molded substance. The incorporation of such cushioning material is advantageous because upon the setting of the concrete or other relatively rigid foundation certain small clearance between the portions of the rail body occur. And after a time the wear on the body allows for a limited amount of relative play between the rail and the concrete base. And the interposition of the yieldable material between the concrete portion and the rail chair serves as an effective cushion and also has a tendency to serve somewhat as a noise deadener.

5 10 15 While we have described quite precisely the specific details of the embodiment of the invention herein illustrated, it is to be understood that the drawing and detailed disclosure are to be interpreted in an illustrative rather than a limiting sense and the claims are intended to cover the specific points of improvement hereinafter defined and various equivalents thereof.

20 25 30 35 40 45 50 55 What we claim is:—

1. A monolithic track structure comprising a cast foundation formed in situ, a rail and rail chair embedded therein, said chair being of bar stock of uniform thickness throughout and having a central depressed portion of a width corresponding to the base width of the rail, clip bearing surfaces in a plane thereabove, rail clips and holding means coacting with said bearing surfaces and downwardly diverging supporting legs depending from said bearing surfaces.

2. A monolithic track structure comprising a rail chair embedded in a body of concrete, said chair consisting of a single continuous bar of uniform rectangular cross sectional area throughout its length and having a central depressed rail seat, upwardly bent shoulder portions at the opposite extremities of said seat for engagement with the edges of the rail base, clip bearing portions extending outwardly from said shoulders and supporting legs extending downwardly from the outer extremities of the clip bearing portions, hold down clips fulcrumed on the clip bearing portions, bolts with integral heads below said clip bearing portions and prevented from turning by said shoulder portions and having shanks extending through the clip bearing portions and said clips and carrying nuts engaging the clips.

3. A monolithic track structure comprising a rail and a rail chair embedded in the body of concrete formed in situ, said rail chair consisting solely of a single metal bar of uniform thickness throughout, bent to form a depressed central portion to suit the width of the rail base, clip

bearing portions located in a plane above the depressed portion, clips fulcrumed thereon and engaging the rail base, securing means for said clips, diverging legs depending downwardly from said clip bearing portions and outwardly curved bearing feet at the lower extremities of said legs.

4. A monolithic track structure comprising a pair of rails, duplicate chairs and other coacting

instrumentalities as defined in claim 3 and a separate spacing bar extending transversely from one chair to the other and secured to the opposed chair legs at its ends having angularly bent portions.
